INVENTOR.

UNITED STATES PATENT OFFICE.

FERDINAND G. RUX, OF TIGERTON, WISCONSIN, ASSIGNOR OF ONE-HALF TO GEORGE H. DREWRY, OF WALDO, WISCONSIN.

MAP-CASE.

1,070,989.

Specification of Letters Patent.

Patented Aug. 19, 1913.

Application filed June 6, 1912. Serial No. 701,966.

To all whom it may concern:

Be it known that I, FERDINAND G. RUX, a citizen of the United States, and resident of Tigerton, in the county of Shawano and 5 State of Wisconsin, have invented new and useful Improvements in Map-Cases, of which the following is a description, reference being had to the accompanying drawings, which are a part of this specification.

10 This invention relates to improvements in map cases, and more particularly to that type which is adapted to be suspended from a support and to hold a number of maps.

15 It is one of the objects of this invention to provide a map case which is adapted to hold a plurality of maps and permit them to be independently withdrawn from the case and exposed to view, and to automatically remain in open or exposed position until re-

20 leased.

25 A further object of the invention is to provide a map case which is adapted to hold reversible maps and which may be swung around on its support to permit either side of the map being viewed.

30 A further object of the invention is to provide a map case adapted to hold a number of maps and which may be revolved to turn the case in position to withdraw the particular map desired to be viewed.

35 A further object of the invention is to provide a map case provided with means for automatically holding the case in the position to which it has been swung or revolved.

40 With the above and other objects in view, the invention consists of the improved map case and its parts and combinations, as set forth in the claims, and all equivalents thereof.

45 In the accompanying drawing in which the same reference characters indicate the same parts in all of the views: Figure 1 is a side view of the improved map case, parts being broken away and other parts being

50 shown in section; Fig. 2 is a transverse sectional view thereof taken on line 2—2 of Fig. 1, parts being broken away; Fig. 3 is a transverse sectional view thereof taken on line 3—3 of Fig. 1; and, Fig. 4 is a detail view of one of the map roller plugs.

55 Referring to the drawing the numeral 8 indicates a supporting wire which is adapted to extend across a school or other room and upon which a carriage bar 9 rides. The carriage is provided with pulleys 10 at its outer

ends through which the wire loosely extends. A horizontally extending supporting bar 11 medially pivotally connected to the medial portion of the carriage by a pivot bolt 12 is provided at opposite ends with bearing brackets 13 through which extends the shaft 14 of the tubular case 15. To cause the supporting bar to snugly engage the carriage bar, a coiled spring 16 surrounding the pivot bolt and interposed between the carriage bar and the nut 12' threaded on the upper end of the bolt, is provided which holds the bars in close engagement and also permits the supporting bar to be freely turned with relation to the carriage bar. The bolt opening of the upper portion of the carriage bar is counterbored to provide a recess 9' to accommodate the spring 16.

The case 15 comprises two heads 17 and 18 mounted fast on the shaft 14, and between which heads a sheet metal tubular map holder 19 is interposed. The ends of the map holder are inserted in circular grooves 20 formed in the heads to securely fasten the holder to the heads. The metal of the case is bent to form, in cross section, approximately an outer cylindrical shell 21 and a plurality of inner parallel tubular holders 22 having elongated slots 23 extending the entire length of the said tubes and through the cylindrical shell. The tubes are adapted to hold the maps 24 with the free ends of the maps extending through the slots so they may be easily withdrawn therefrom by pulling on the reinforcing strips 25 fastened to the outer ends of the maps. The reinforcing strips are of larger diameter than the width of the tube slots and also serve to prevent the map ends from being drawn into the tubes. A medial reinforcing block 26 shaped to conform to the inner contour of the cylindrical casing and the tubular portions thereof serves to strengthen the parts. The head 17 is provided with openings 27 which register with open ends of the tubes to permit the maps to be inserted therethrough and into the tubes. The head 17 is further provided with slots 28 extending at an angle from the openings 27 to the periphery of the head, and these slots register with the slots of the tubes to permit the maps to be placed within the tubes with the free ends thereof extending through the slots. The maps are adapted to have their

inner ends fastened to ordinary spring retrieved window shade rollers 29 of the automatic type which are provided with dogs 30 to hold the roller in adjusted position. The 5 pindle ends 31 of the rollers are journaled in the head 18 and the flattened spring holding keys 32 of the opposite ends of the roller are adapted to be extended into the elongated recesses 33 of the tapered plugs 34. These 10 plugs fit snugly within the openings of the head 17 and are provided with locking pins or screws 35 projecting from their peripheries which enter the locking recesses 36 of the head 17. In order to securely and 15 removably hold the plugs in the head a cap 37 is provided which is journaled on the shaft 14 and bears against the outer face of the head and plugs. The cap is provided with an opening 38 extending to the periphery 20 of the cap and the cap is adapted to be turned by means of the handle 39, to bring the opening into register with the plug it is desired to remove. The shaft 14 is provided with handles or knobs 40 and 41 for convenience in turning the case and a coiled 25 spring 42 surrounding the handle and interposed between the handle 40 and the depending bracket 13 adjacent thereto is adapted to frictionally hold the cylindrical casing in adjusted position.

In use double faced maps are preferably fastened to the rollers and wound thereon and the rollers are then inserted in the map tubes and the plugs are placed within the 30 head openings and in engaging position with the flattened spring holding keys. The entire device may now be slid on the supporting wire to the desired place in the room and the case revolved until the map tube holding 35 the map wanted is in the lowermost position. The map is now pulled down and out of the map tube to expose the map to view and the map will be held in this position by the locking dogs until released by a slight downward pull when the spring of the roller will 40 automatically draw the map into the tube. If it is desired to view the opposite side of the map the supporting bar is swung around on the carriage bar until the other side is in 45 front.

From the foregoing description it will be seen that the map case is adapted to hold a plurality of maps which may be easily, independently viewed when desired.

50 55 What I claim as my invention is:

1. A map case, comprising a supporting member having depending arms, a shaft journaled in said arms, cylinder heads mounted on said shaft, one of said heads 60 provided with a plurality of tapered openings, tapered plugs extending into said openings, a plurality of tubular map holders interposed between and connected to said heads and provided with elongated slots, one 65 of the ends of each tubular holder register-

ing with one of the openings of one of the heads, and spring actuated map rollers journaled within the holders and having one end portion engaging the plugs and held thereby.

2. A map case, comprising a supporting 70 member having depending arms, a shaft journaled in said arms, cylinder heads mounted on said shaft, one of said heads provided with a plurality of openings and slots extending from said openings to the periphery of the head, a plurality of tubular map holders interposed between and connected to said heads and provided with elongated slots which register with the slots of the head, one of the ends of each tubular 75 holder registering with one of the openings of the head, plugs extending into the openings of the heads and provided with medial elongated recesses, the outer portions of said plugs being of larger diameter than their 80 inner portions, and spring actuated map rollers positioned within the map tubes and journaled at one end in one of the heads and having their other end portions extending in the medial elongated recesses of the plugs. 85

3. A map case, comprising a carriage, a supporting member medially pivotally connected thereto and having depending arms, a cylindrical casing revolvably connected to the depending arms of the supporting member 90 and provided with a plurality of map spaces, said casing provided with elongated slots communicating with the map spaces, and map rollers positioned within the spaces and having maps rolled thereon which extend through the elongated slots. 100

4. A map case, comprising a carriage, a supporting member medially pivotally connected thereto and having depending arms, a cylindrical casing revolvably connected to 105 the depending arms of the supporting member and provided with a plurality of map spaces, said casing provided with elongated slots communicating with the map spaces, heads forming part of the casing, one of said 110 heads provided with a plurality of openings communicating with the map spaces and with slots registering with the elongated slots of the casing, tapered plugs extending into the openings of the heads, and map 115 rollers positioned within the spaces and having maps rolled thereon which extend through the elongated slots.

5. A map case, comprising a carriage, a supporting member medially pivotally connected 120 thereto and having depending arms, a cylindrical casing revolvably connected to the depending arms of the supporting member and provided with a plurality of map spaces, said casing provided with elongated 125 slots communicating with the map spaces, heads forming part of the casing, one of said heads provided with a plurality of openings communicating with the map spaces and with slots registering with the elongated 130

slots of the casing, plugs extending into the openings of the heads, the outer portions of said plugs being of larger diameters than their inner portions, a cap positioned adjacent to the head and covering the openings thereof and provided with an opening, said cap adapted to be turned so that its opening may register with any opening of the cover and map rollers positioned within the spaces

and having maps rolled thereon which extend through the elongated slots.

In testimony whereof, I affix my signature, in presence of two witnesses.

FERDINAND G. RUX.
